UNITED STATES PATENT OFFICE.

JAMES M. MACDONALD, OF EAST ORANGE, NEW JERSEY.

HEAD-LIFTING DETECTOR FOR GOLFERS.

Application filed August 23, 1922. Serial No. 583,763.

To all whom it may concern:

Be it known that I, JAMES M. MACDONALD, a citizen of the United States of America, residing at East Orange, in the county of 5 Essex and State of New Jersey, have invented certain new and useful Improvements in Head-Lifting Detectors for Golfers, of which the following is a full, clear, and exact description.

10 In playing the game of golf with anything approaching proficiency, there are certain fundamental principles or rules which beginners must learn and which adepts are constantly violating, and one of the most 15 stringent of these is concisely expressed in the injunction to "keep your eye on the ball". A skilled player or teacher by observing a person making his stroke, can readily tell when this injunction is not followed, but in his absence the player learns 20 the fact only by the disastrous and discouraging result of looking up while making his stroke.

I have devised a device of very simple 25 character which any player may profitably use that gives an unfailing indication of any violation of this rule, and thus enables either a tyro or an expert to see at once if he is going astray in this most important requirement of the game. This device forms the 30 subject of my present application for Letters Patent.

In general terms the improvement consists 35 of a frame, usually and conveniently an ordinary spectacle frame, either with or without glasses or lenses, which is provided with a transverse rail or guide, not in the direct line of vision, but sufficiently near it to be readily seen, and on or over this guide there 40 is a traveling opaque object such as a bead, pendant or any other suitable small object which normally, or so long as the guide or longitudinal axis of the frame is in a horizontal position, rests at one end of the same, 45 but the moment the guide or axis is inclined to the horizontal, which occurs whenever the wearer looks up from the ball, then the bead or other object travels along the guide and across the field of vision of the player, 50 showing him that he has not "kept his eye on the ball".

Manifestly, the objects of the invention are secured to the full by many modified forms of this device. For example, the object which crosses the field of vision when

the player looks up from the ball need not necessarily slide over or along a rail or guide, as it might be brought in other ways by the force of gravity into view. It is not essential that the object travel entirely across the field of vision of both eyes, provided its movement be sufficient to effect the desired impression upon the player, but in practice I have found the device which I shall hereinafter illustrate and describe as the best 65 adapted for general purposes and it is the preferred form of the improvement.

In the drawings hereto annexed:

Fig. 1 is a view in elevation of what I term a frame to which my improvement is 70 applied.

Fig. 2 is a side view of the same.

Fig. 3 shows the details of the means for attaching the guide to the frame.

Fig. 4 is a sectional view on the line 4-4 75 of Fig. 2.

Fig. 5 is a view in elevation of a modified form of eye-glass or spectacle frame with the improvement attached.

Fig. 6 is a sectional view on the line 80 6-6 of Fig. 5; and

Fig. 7 is a side view of a portion of Fig. 6.

The support for the guide, as above stated, may be a regular or a modified form of 85 spectacle frame 1, as shown in Fig. 1, and it may have glasses or lenses or not, as desired.

Carried by this frame is a transverse guide bar 2 of any desired shape and proper character, on which there is mounted and free to slide or travel an opaque object such as a bead or ball 3. The guide bar is supported from the frame by arms 4 in front of and somewhat above the same so as to be near but not directly in the line of vision. 95

To enable the device to be folded and packed in an ordinary spectacle case, the arms 4 are pivoted between the sides of a metal piece 5, pressed up from sheet metal which has two projections 6, adapted to 100 pass over the joint between the frame and the bows 7 and to be secured thereto by the screw 8. The arm 4 has small projections 9 on its sides that enter holes 10 in the piece 5, the sides of which have more or less spring, and this holds the said arms in operative position in use. They may, however, be freed from this partially locked position when the arms are turned by hand to the position indicated by dotted lines in 110

Fig. 2 to collapse or close the device for insertion into a spectacle case.

The character of the supporting frame is not of the essence of the invention. For example, in Fig. 5 is shown a form of eyeglass that is pched to the nose. The arms 4 when used with such a device are conveniently pivoted to parts 5 which are passed down over projections 11 and secured, 10 if need be, by nuts 12.

If bows are used with this or other form of frame they may be adjustable with respect thereto by a slot attachment 13, as shown in Fig. 7, by which means the distance of the guide from the eyes of the player 15 may be varied at will.

Normally, with a right-hand player the ball or bead is normally at the left-hand end of the guide as one faces it, but with a left-hand player it is at the other end as shown in Fig. 1. As stated, its limit of travel 20 may be fixed at anything less than the full length of the guide. For example, the guide may have a bowed portion at the center and at ends which limits the travel 25 unless the head is turned too high.

Manifestly, from the above description, if a player looks steadily at his ball while addressing it and then raises his head to 30 watch the flight of the ball after it is struck, the bead travels across the field of vision notifying him that he has done wrong. This device, therefore, is most useful in teaching one to play properly in this re- 35 gard.

What I claim as my invention is—

1. A device for golf players of the kind herein described comprising in combination a frame adapted to be worn like a pair of spectacles, a transverse guide carried thereby somewhat out of the direct line of vision and an object adapted to travel along such guide from one side of the same when such guide is inclined to the horizontal. 40

2. A device for golf players' use comprising a spectacle frame, a bar carried by the same somewhat above the direct line of vision, and an object adapted to travel along said bar when it is inclined to the horizontal. 45

3. A device for golf players' use comprising a frame to be worn in front of the eyes, a transverse guide bar carried by the same somewhat above the direct line of vision, arms supporting said bar and pivoted to the frame and adapted to be turned when the device is closed to be put in a case, and an opaque ball or the like movable freely over the guide bar. 55

4. A device for golf players, of the kind herein described, comprising a transverse guide adapted to be supported on the head of the player and somewhat out of the direct line of vision and an object adapted to travel along such guide from one side of the same when the head is raised and the guide inclined to the horizontal. 60

In testimony whereof I hereto affix my signature.

JAMES M. MACDONALD.
